ABSTRACT

A temperature compensation network having a resistance that exhibits a temperature coefficient that is adjustable substantially independently of the voltage applied to the network. The network includes a resistive voltage divider connected in parallel with the emitter-collector path of a transistor. The base of the transistor is connected to a tapping on the voltage divider. A zener diode having a zero temperature coefficient relative to the transistor temperature coefficient is connected to the voltage divider, whereby the network exhibits a net negative temperature coefficient of resistance.

NETWORK HAVING A RESISTANCE THE
TEMPERATURE COEFFICIENT OF WHICH IS
VARIABLE AT WILL

The present invention relates to a network having a resistance with a temperature coefficient that is variable at will. Such networks are often required, especially in semiconductor technology, in order to compensate for the temperature coefficient of an entire circuit arrangement or of an important part thereof.

The British Pat. specification No. 1,093,316 describes a circuit arrangement for compensating the temperature-dependent variations of a current flowing through a temperature-dependent element supplied through the emitter-collector path of a first transistor, the current flowing through the said transistor being controlled by a control magnitude. According to this patent, the control circuit includes, for temperature compensation, the emitter-collector path of a further transistor having a resistive voltage divider connected in parallel therewith and to the tapping of which the base of the further transistor is connected. The resistance value of the part of the voltage divider connected between the emitter and the base of the further transistor is smaller than the value of the base-emitter input impedance of the further transistor, and the current through the whole of the voltage divider is smaller than the collector current of the further transistor. This arrangement thus mainly comprises a network having a resistance with a temperature coefficient that is variable at will and including the parallel connection of a resistive voltage divider and the emitter-collector path of a transistor the base of which is connected to the tapping of the voltage divider.

The temperature coefficient C_{tot} of this network is equal to the temperature coefficient C_{tr} of the internal base-emitter resistance of the transistor multiplied by the ratio V_s/V_{be} between the voltage set up across the network (V_s) and the voltage operative between the base and the emitter (V_{be}) of the transistor. Consequently, C_{tot} is also influenced by the choice of V_s and it is not possible to obtain a given desired value of C_{tot} for each arbitrary value of V_s . For a given value of C_{tot} a variation of V_s requires a proportional variation of V_{be} . Therefore a variation of the value of one of the resistors of the resistive voltage divider requires a variation of the value of the other resistor thereof. As a result, it is difficult to achieve the desired adjustment. In an embodiment of the circuit arrangement described in the above-mentioned patent specification, this difficulty is avoided by feeding the base-emitter circuit of the transistor of the network, more or less independently of V_s , from a separate supply source through a variable resistor connected to a second tapping on the part of the resistive voltage divider which is connected between the base and the emitter of the transistor.

It is an object of the invention to provide an improved network of the kind described, the temperature coefficient of which can be chosen substantially independently of the reverse collector voltage set up across the network, no separate supply source for the base-emitter circuit of the transistor being required.

According to the present invention an element having a temperature coefficient substantially equal to, and including at least one Zener diode, is connected in the voltage divider so that the temperature coefficient of the network can be chosen substantially independently of the reverse collector voltage set up across the network.

In order that the invention may readily be carried into effect, it will now be described in greater detail, by way of example, with reference to the accompanying drawing, in which:

FIG. 1 is the circuit diagram of the network used in the arrangement described in British Pat. specification No. 1,093,316.

FIG. 2 is the circuit diagram of a modification of this network described in the said patent specification.

FIG. 3 is the circuit diagram of a first embodiment of the network in accordance with the invention.

FIG. 4 is the circuit diagram of a second embodiment thereof, and

FIG. 5 is the circuit diagram of a third simplified embodiment thereof.

FIG. 1 shows the network described in British Pat. specification No. 1,093,316 and having a temperature coefficient which is variable at will. This network is constituted by the parallel connection of the resistive voltage divider comprising resistors 2, 3 and 4 and of the emitter-collector path of a transistor 1, for example, an NPN-transistor, the base of which is connected to the junction of the resistors 2 and 3 of the voltage divider. The value of the part 2 of the voltage divider connected between the emitter and the base of the transistor 1 is made smaller than that of the base-emitter input impedance of the transistor 1. The overall resistance $R_s = R_2 + R_3 + R_4$ of the voltage divider 2, 3, 4 is chosen to be such that the current I_s flowing through this voltage divider is smaller than the collector current I_c of the transistor. At a given reverse collector voltage $+V_s$ this is accomplished by making the value R_2 of the resistor 2 small as compared with the forward base-emitter resistance R_{be} of the transistor 1, and by making the overall resistance value $R_s = R_2 + R_3 + R_4$ of the voltage divider such that

$$V_s/R_s < I_c$$

The collector current I_c is equal to $(\alpha' - 1)$ times the base current I_b , which in turn is equal to the quotient V_{be}/R_{be} (the base-emitter voltage divided by the base-emitter resistance). Since R_2 is made smaller than R_{be} , V_{be} is about equal to V_s . R_s/R_2 , but R_{be} is dependent on the temperature and also on V_{be} and hence on V_s .

The collector current I_c and consequently the overall resistance R_N of the network also vary with temperature and under the conditions set forth, the temperature coefficient C_{tot} of this variation is equal to V_s/V_{be} , or approximately R_s/R_2 , times the temperature coefficient C_2 of the base-emitter resistance of the transistor, provided that the collector-base current gain factor $\alpha' - 1$ of the transistor is greater than the feed-back factor R_s/R_2 which limits the gain.

Varying the voltage V_s causes the base-emitter voltage V_{be} and hence the base current I_b and the collector current I_c to vary, which usually is undesirable. Subsequent readjustment of the collector current I_c to the desired value, for example, by varying the resistor 4, involves a change in the ratio R_s/R_2 and hence in the total temperature coefficient C_{tot} , which consequently can be selected only in a given relationship with the voltage V_s .

The modification shown in FIG. 2 and described in the above-mentioned patent specification has 1° of freedom more. In this arrangement the resistive voltage divider is provided with a second tapping between two parts 2 and 2' of its base branch, its collector-base branch comprising only the resistor 3. The second tapping is connected through a further resistor 5 to separate voltage source $+V_g$ of, for example, constant or stabilized forward base voltage.

The resistive voltage divider 2, 2', 3 satisfies the above conditions so that:

$$R_2 + R_{2'} < R_{be} \text{ and} \\ V_s/R_s < I_c$$

where $R_s = R_2 + R_{2'} + R_3$;

The voltage V_g of the auxiliary voltage source and the value of the resistor 5 are chosen so that the forward base-emitter voltage V_{be} and the base-current I_b are mainly determined by these magnitudes and that the resistance value R_5 of the further resistor 5 has substantially no influence on the effective value of the base-emitter branch of the voltage divider 2, 2':

$$\frac{V_g}{R_5 + R_2} > \frac{V_s}{R_s}$$

$R_5 \gg R_2$, and preferably $V_g > V_s$.

Under these conditions V_s may be changed without large changes in V_{be} , I_b , I_c and C_{tot} , and I_c may be adjusted by varying V_g , R_5 or the ratio between R_2 and $R_{2'}$, without greatly influencing the ratio

$$\frac{R_s}{R_2 + R_{2'}}$$

and hence the overall temperature coefficient

$$C_{tot} = C_{tr} \cdot \frac{R_s}{R_2 + R_2'}$$

This circuit arrangement has the disadvantage of requiring a separate voltage source having a substantially constant voltage relative to the emitter of the transistor 1 must be substantially constant. Nevertheless, there is still a slight but inevitable influence of the adjustment of I_c on the value of C_{tot} .

In the embodiment of the network in accordance with the invention shown in FIG. 3, the resistive voltage divider comprises a resistor 2 connected between the base and the emitter of a transistor 1 and a resistor 3 with the end remote from the base connected to the tapping on a further resistive voltage divider 9, 9'. The latter voltage divider is connected in parallel with a Zener diode 7, this parallel connection being connected at one end to the voltage source $+V_s$ and at the other end through a resistor 8 to the emitter of the transistor 1. This network also satisfies the above conditions:

$$R_2 < R_{be}$$

$I_c >$ the current through the voltage dividers $= I_8 + I_3$, where

$$I_8 = \frac{V_s - V_7}{R_8}$$

and

$$I_{3max} = \frac{V_s}{R_3 + R_2 + R_3}$$

Furthermore,

$$\frac{R_9 \cdot R_{9'}}{R_9 + R_{9'}} \text{ or } \frac{R_9 + R_{9'}}{4}$$

must be small as compared with R_3 .

Under these conditions the temperature coefficient of the network is

$$c_{tot} = R_s / R_2 \cdot C_{tr} + R_9 / R_9' C_7$$

where C_7 is the temperature coefficient of the Zener diode 7. This Zener diode may be selected to have a very small temperature coefficient, for example, a coefficient which compared with that of the transistor, C_{tr} , is substantially equal to zero. The Zener voltage V_7 across the diode 7 must be at least equal to the desired range $V_{smax} - V_{smin}$ of the voltage across the network. If for the desired value of V_7 no Zener diode 7 having a temperature coefficient of substantially zero can be found, this diode may be replaced by the series connection of one or several Zener diodes 7, 7' and one or several diodes 10, 10' connected in the forward direction, the Zener diodes and the other diodes being chosen so that the desired overall voltage drop $V_z = V_7 + V_{7'} + V_{10} + V_{10'}$, is obtained and the temperature coefficient C_z of the Zener diode is compensated for by that of the other diodes:

$$C_z = C_7 + C_{7'} + C_{10} + C_{10'} \approx 0$$

Under these conditions, the overall temperature coefficient C_{tot} of the network may be freely chosen by means of the ratio R_3/R and of the temperature coefficient C_{tr} of the transistor 1, while independently thereof the collector current I_c and consequently the voltage V_s across the network may be varied within given limits by varying the voltage across the voltage divider 2, 3.

The collector circuit of the transistor 1 further includes a protective resistor 6 for limiting I_c to a permissible value, for example, in the case of an excessive voltage across the voltage divider 2, 3:

$$R_6 \geq V_{smax} / I_{cmax}$$

In an arrangement including temperature-sensitive elements which is to be controlled in accordance with the value of the

voltage V_s , the described network may be used as a temperature-dependent compensating resistor having a temperature coefficient which is adjustable or variable at will. Alternatively, the network may be used as a first stage of the arrangement which compensates for the influence of the temperature, the control voltage for the next stage being derived either between the emitter and the collector of the transistor 1 or, with inversion of the temperature influence, across the resistor 6.

FIG. 4 is the circuit diagram of a second embodiment of the network in accordance with the invention.

In this embodiment the Zener diode 7 is connected in series with two diodes 10 connected in the forward direction so that its temperature coefficient is compensated. The series connection of the diodes 7 and 10, shunted by the voltage divider 9, 9', is included in the first voltage divider between the resistors 2 and 3. Since the temperature coefficient of the section 7, 10 is substantially equal to zero, the overall temperature coefficient C_{tot} again is equal to

$$\frac{R_2 + R_3}{R_2} \cdot C_{tr}$$

25

and hence can be chosen by means of the resistors 2 and 3, while independently thereof the working point of the transistor 1 can be determined by means of the second voltage divider 9, 9'.

30 In many applications it is not necessary for I_c and hence for V_s to be variable, but the desired invariable value of I_c is smaller than corresponds with the ratio R_3/R_2 determined by C_{tot} . In such cases the simplified modification shown in FIG. 5 may be used:

35 C_{tot} may be freely chosen by means of the temperature coefficient C_{tr} of the transistor and of the ratio R_3/R_2 , while independently thereof V_s and hence I_c can be freely chosen by means of $V_z = V_7 + V_{7'} + V_{10} + V_{10'}$.

40 The networks in accordance with the present invention are especially intended for use in series with other elements, such as resistors, so as to compensate for the temperature coefficient or coefficients either of one or more further elements of a circuit or arrangement, or of an entire circuit or arrangement,

45 for example, as described in the above-mentioned British Pat. specification No. 1,093,316. At the same time they may serve as input stages of such circuits or arrangements.

I claim:

50 1. A temperature dependent network having a resistance with a temperature coefficient that is variable at will comprising, a transistor, a plurality of resistance elements connected to form a resistive voltage divider, means connecting the resistive voltage divider in parallel with the emitter-collector path of the transistor, means connecting the base of the transistor to a tapping on the voltage divider so that the resistance value of the part of the voltage divider connected between the emitter and the base of the transistor is smaller than the value of the base-emitter input impedance of the transistor, the overall resistance value of the voltage divider being chosen so that the current through the whole of the voltage divider is smaller than the collector current of the transistor, an element having a temperature coefficient that is substantially equal to zero relative to the transistor temperature coefficient and including at least one Zener diode, and means connecting said element in the voltage divider so that the temperature coefficient of the network can be chosen substantially independently of the reverse collector voltage set up across the network.

3. A network as claimed in claim 1, characterized in that the element including the Zener diode is connected to the emitter of the transistor through a resistor.

4. A network as claimed in claim 4, characterized in that the collector circuit of the transistor includes a further resistor.

5. A network as claimed in claim 1 wherein the last-named connecting means is arranged to connect a part of the resistive voltage divider in parallel with said zero temperature coefficient element, and means connecting a tapping on said parallel part of the voltage divider to the base of the transistor.

6. A temperature-sensitive network with a temperature coefficient of resistance that is adjustable substantially independently of the voltage applied to the network comprising, a pair of input terminals, a transistor with a given temperature coefficient, a constant voltage element with a temperature coefficient that is negligible relative to said given temperature coefficient of the transistor, a resistive voltage divider, means connecting the constant voltage element in series with the voltage divider across the network input terminals, and means connecting the emitter-collector path of the transistor in parallel with the resistive voltage divider and the base electrode to a tapping on the voltage divider such that the resistance of the part of the voltage divider between the base and emitter of the transistor is smaller than the transistor base-emitter input impedance.

7. A network as claimed in claim 6 wherein said constant voltage element comprises a Zener diode in series with a diode of approximately equal and opposite temperature coefficient.

8. A network as claimed in claim 7 wherein said Zener diode and diode are connected in series in that part of the voltage divider connected between the base and collector of the transistor.

9. A network as claimed in claim 6 wherein said constant

voltage element comprises a Zener diode, said network further comprising a second resistive voltage divider connected in parallel with the Zener diode, and wherein the base electrode of the transistor is directly connected to a tapping on the second voltage divider.

10. A network as claimed in claim 9 wherein the first voltage divider comprises first and second resistors, and wherein said first resistor, said Zener diode and said second resistor are serially connected in the order named across the network input terminals.

11. A network as claimed in claim 6 further comprising a second resistive voltage divider connected in parallel with said constant voltage element, and means connecting a tapping on said second voltage divider to the base of the transistor.

15 12. A network as claimed in claim 13 wherein said constant voltage element comprises a Zener diode.

13. A temperature sensitive network with a temperature coefficient of resistance that is adjustable substantially independently of the voltage applied to the network comprising, a pair of input terminals, a transistor with a given temperature coefficient, a zener diode with a temperature coefficient that is negligible relative to the transistor temperature coefficient, a first resistive voltage divider, a second resistive voltage divider connected in parallel with the zener diode and across the

20 input terminals, means connecting the first voltage divider to a tapping on the second voltage divider, and means including a part of said second voltage divider for connecting the emitter-collector path of the transistor in parallel with the first resistive voltage divider and the base electrode to a tapping 25 thereon such that the resistance of the part of the first voltage divider between the base and emitter of the transistor is smaller than the transistor base-emitter input impedance.
